COMBINED DATA TRANSMITTER AND CARD PUNCH

Walter M. Beusse, Niles, Ill., assignor to Teletype Corporation, Skokie, Ill., a corporation of Delaware

Filed Apr. 1, 1966, Ser. No. 1,725

Term of patent 14 years

(Cl. D26—5)

FIG. 1

FIG. 2

FIG. 3

FIG. 1 is a front perspective view of a combined data transmitter and card punch, showing my new design;

FIG. 2 is a rear perspective view thereof; and

FIG. 3 is an enlarged right-side elevational view thereof.

The dominant features of my design reside in the portions shown in full lines, it being understood that the keys are continuous within the area indicated in broken lines in FIGS. 1 and 2.

I claim:

The ornamental design for a combined data transmitter and card punch, substantially as shown and described.
